Patented Sept. 10, 1918.

UNITED STATES PATENT OFFICE.

THOMAS C. SPELLING, OF NEW YORK, N. Y.

SHIFTABLE STOPPER.

1,278,244.

Specification of Letters Patent. Patented Sept. 10, 1918.

Application filed January 22, 1917. Serial No. 143,780.

To all whom it may concern:

Be it known that I, THOMAS C. SPELLING, citizen of the United States, and resident of the city of New York, in the county of New York and State of New York, have invented certain new and useful Shiftable Stoppers, of which the following is a specification.

This invention relates to combinations of caps and pullers with shiftable stoppers for bottles and containers for liquids and other substances.

Its purpose is the provision of a simple economical and effective means for pouring out of bottles and other containers liquids and other substances without the necessity of removing the stopper from the bottle or container. It is especially useful in cases of liquids, oils, syrups and mucilaginous substances which stain, grease, corrode, burn or adhere; but the device is of extensive adaptability, and in modified forms may be used in connection with substances other than liquids.

To facilitate a full and complete understanding of the invention, I will illustrate the preferred and also a modified embodiment of the same, and the details, arrangement and combination of parts will be learned upon reading the specific description found hereinafter, in connection with the accompanying drawings, forming a part hereof, wherein the preferred and modified embodiments are illustrated.

Figure 1 is a sectional view of a container equipped with the device as it will appear ready for the flow of liquid therefrom at the sidemouth; Fig. 2 is a perspective view of the bottle-neck member prepared for equipment with the other parts; Fig. 3 is a perspective view of the cover member, showing the edges of the cap abutting and held rigid by means of an angle brace riveted thereto and designed to function as a support, the protector to be later described; Fig. 4 is a perspective view of the pull member, (hereinafter designated as the puller) exhibiting its principal parts in positions and relations to be occupied and held by them after insertion in the stopper and prior to the application of pull force; and Figs. 5 and 6 are sectional views of the positions and relations of the same parts after being set, as a result of applying initial pull force. Fig. 7 is a perspective view of the part of the puller hereinafter designated as the sharp clip, and Fig. 8 is a like view of the part hereinafter designated as the blunt clip. Fig. 9 represents a modification.

Referring more specifically to the drawings wherein like reference figures designate corresponding parts, 1 is a stopper, of any material of which a stopper may be suitably formed and at 2 is an opening, preferably a gap or groove, the uses of which are made apparent hereinafter. The bottle neck member has the mouth 3, the sidemouth 4 and the slot or gap 5. The cover member has corresponding gaps cut away at 6 to form the opening 7 upon emplacement. The puller has the ring or shield 10 on the stem 11, the sharp point 12, the slots 13 to receive and engage the narrowed portions 14 of the clips. At 14^a, the sides of the stem which are to be adjacent to the depressed shoulders of the clip, with the latter in place, are slightly flattened, thus forming a shallow groove therein, the rotundity of the stem being thus modified, the purpose being to so locate said shoulders in place that they will not seriously interfere with the introduction of the stem to place. The sharp edged clip has the said narrowed portion, the depressed shoulders 15 the wings 16 on which are the sharp edges 17 and the sharp and slightly deflected points 18. The blunt edged clip has the same parts designated by the same reference figures, and differs from the sharp edged clip only in the respect that the said edges 17 are blunt. Each slot slants from each side of the stem to a common base 19, the narrowed portion of the clip being bent upon insertion to fit and be frictionally held therein.

In order to facilitate insertion of the stem in the stopper, the interior or upper, walls of each slot are beveled at 19^a so that, in descending to place, the wings may fold up against the stem. The clips are placed in the stopper at right angles with the incisions or openings in stopper, cover, and bottle, the purpose being the prevention of interference in use of one operation with another, and in order that integral portions of the bottle neck and stopper shall be adjacent to the wings.

Further description will consist largely of a description of the process of emplacement of parts and their operation in use. The stem is introduced into the stopper along its center, the stem point preceding the other adjuncts, small trenches being cut by said sharp wing points and the stopper substance

being impacted and possibly slightly torn by the wings, the shoulders not interfering, however, because screened from contact by emplacement in said flattened portions of the 5 stem. When the ring contacts with the cap, (presently described) on the top surface, the proper depth has been attained by the other parts respectively. The stem is then, by the application of pull force at the ring, caused 10 to move upwardly a short distance, the length of the movement being regulated by the action of the wings and wing shoulders. The sharp points 18 of the sharp clip, initially enveloped in the stopper substance, 15 are, by said pull force, caused to further penetrate at an angle with respect to the stem and upwardly and outwardly in the stopper substance, and the sharp edges cut their ways in the general direction taken by said wing 20 points. The blunt wings will simultaneously indent the stopper substance and impact it out toward the inside surface of the neck, probably with incidental but immaterial splitting and tearing.

25 This puller provides a convenient simple means for upwardly moving all kinds of stoppers, whether tapered or straight in form, whether loosely or tightly emplaced. The difficulty encountered in upwardly moving 30 stoppers is the adhesion at the surface, resulting from tense contact with the inner surface of the neck of the bottle, and a hardening of the outer surface of the stopper, resulting from an inevitable access of atmosphere. The interiors of stoppers remain 35 comparatively soft, and barbs and wings centrally located and not, as here, supplemented, usually, especially in the case of tight stoppers, cut their ways upwardly, or tear out the 40 interior, or break and dismember the stopper, leaving either the outer or lower portion in the neck. Usually, the use of a clip having comparatively blunt edged wings alone would effect a removal of the stopper.

45 Such a sharp edged wing as is here provided is, however, a valuable auxiliary, because of its lifting capacity. Yet uniform success of the pulling process cannot be expected without the coaction of the other clip, with 50 its blunt edged wings. The full force will act simultaneously upon both. The sharp edged wings will carve into the stopper substance with but slight if any effect upon form, but, while its action resulting from a 55 continuance of the pull force, might cause upward movement of the portion above it, it would, in most cases, merely result in a severance of the cork. The blunt winged clip is located on the stem a little below the 60 sharp winged clip. The pull force produces a different effect upon it. As its wings are forced outwardly and at an angle upwardly, they produce a perceptible separation of the adjacent parts, and indent, without cutting, 65 the substance. They also have action on the

outer surface, forcing it to slide upward on the interior surface of the neck. Together, the clips exert not merely lifting power but an upwardly and outwardly directed force; and it is clear, without illustration, that any 70 required number of such clips, and of both kinds may be employed on a single stem. The necessity in such a device for an interior rigid member is also obvious. When, as a result of pulling and resultant spreading of 75 the wings, the shoulders have receded to the point of contact with the flattened portions of the stem, the backward movement of the wings is arrested, and not the puller alone but the stopper also must move responsively 80 to a continuance of the pull force. But the effect of the pull force being here interfered with by lock action, we have all the parts of the puller, as regards present purposes, finally 85 emplaced. The sharp clip will rest in place in the upper slot, alined with the blunt clip. Its wings are identical with each other and are identical in general form with the wings of the sharp clip, but the edges of the former are comparatively blunt.

90 The stem shoulder 20, upon the clips being set by initial pull force will be elevated a little above the top surface of the cap on the stopper, the elevation depending on the length of the wings, which in turn will be 95 adapted to the size of the stopper in each case. The buffer 21 rests under the stem shoulder its base resting on the top of the cap on the stopper. The cap, preferably of thin sheet metal, rests on top of the stopper, 100 and has the hole 22 for the stem, also the interior shoulder 23, the interior shoulder 23^a, and the extension 24. When assembled, the top rim of the cork will rest against interior shoulder 23, and the top rim of the neck will 105 rest against interior shoulder 23^a. This extension is a mere continuation of the sheet of which the cap is formed, and has the rivet holes 25 correlated to similar holes 25^a in the cover for fastening these two members together.

110 The extension of the opening made in the neck from the side-mouth to the top is not merely a convenience in the manufacture of the container, but its presence allows a flattening and creasing of the corresponding portion of the cover, affords room for properly fitting and fastening its side edges, and guides the stopper and cover in proper course and relation. Speaking with literal 115 correctness, the cap and tubular formation, constituting Fig. 3, together constitute the cover, but to facilitate illustration and description I have termed the portion made to cover the stopper and extend over the rim of the neck the cap, and the other portion the cover. There is a barely perceptible bend to the horizontal adjacent to reference figure 25 on the cap and between reference figures 8 and 9 on the cover. When the two 120

edges of the cover are brought together and riveted, and the cap and cover are riveted together, and the flattened sections brought into correspondence with each other, and 5 the completed flat section placed across the slot in the neck, (see Fig. 2) such combination will prevent rotary movement of the cover and, in use, the united stopper and cover (the term now including the cap) 10 will be held and guided vertically, with the gap in the stopper in alinement with the side-mouth, 4.

Incidentally to their combined principal office, the stem and clips constitute a much 15 needed bracing and strengthening for the stopper, without which, especially in the case of straight and tight stoppers, they would tend to roughen exteriorly, rendering vertical movement in use difficult.

20 The stopper is first introduced into the neck, through the mouth of the bottle, care being taken to aline the gap or recess therein with the slot and side-mouth in the neck. Next the riveting or soldering whereby the 25 cap and cover and the edges of the cover are united is done on the stopper and neck, and the cover member thus are emplaced, in proper position and relation with respect to the side-mouth, spout and slot in 30 the neck. The cap now rests on the stopper. Next the puller carrying the clips is inserted in the stopper through the hole 22 in the cap, care being taken that the clips be arranged at an angle, preferably at right angles, with a line drawn vertically through 35 the side-mouth. Since, as is self evident, the initial insertion of the stem with the clips in it will require the application of mechanical force, it may be well to explain 40 that, in the process of insertion, the bottle will be clamped, and the stopper firmly held through the side-mouth by any suitable tool which may be employed. A sharply pointed 45 per has no sealing function, hence its slight mutilation, if resulting, would be of no consequence. As initially inserted the wings 50 of the clips slant upwardly against the stem, the sharp points thereon, having cut their ways down, rest enveloped in the substance of the stopper, as before explained, and the points of the depressed shoulders, are near to, but slightly separated from the surface 55 of the flattened side of the stem. It is obvious that, ordinarily, and before upward movement of the stopper can be effected, as a result of the application of pull force, the wings will be given a punching and penetrating movement which quickly causes the 60 depressed shoulders to contact with the stem in the shallow grooves formed by flattening, as above explained; and such contact arrests the backward movement of the wings. The yielding movement now terminating, if the 65 pull force were continued, the stopper would

be moved upwardly. Of course, however, the contents of the container have been already introduced, and upward movement at this stage would be premature. The preliminary pull by which the wings are set results in a slight elevation of the ring above 70 the cap and exposure at that point of a small portion of the stem. Now merely for the purpose of raising the stopper, no buffer under the ring would be needed; but to 75 lower the stopper after any desired use of the side-mouth, the force exerted to replace it and so reseal the bottle below the side-mouth, can be most conveniently exerted on the stem at the ring. Without the buffer 80 20 the stem would have downward movement and disarrange the setting of the clips. So the buffer 20 is provided. It must be emplaced last, on the cap around the hole, 22, but may be placed around the stem in any 85 one of a variety of ways which I think need not be here specified.

After emplacement of the other parts, we shall find the lower margin of the gap, 26, 90 in the cover some little distance below the spout. Thereto may be attached an appropriately formed lug, 27, to evenly contact with the lower side of the spout in the function of arresting upward movement.

The shield 28, carrying the flap or cover 29 95 may be suitably attached to the upper margin. After emplacement, the shield will rest on, and the flap or cover will extend over the spout. They might be variously constructed, but it is here suggested that the 100 shield be in the form of a concaved shell, the open side to be the under side, the edges of the shell to extend slightly beyond the outer form of the spout, and that the flap or cover be attached to the edges of the shell 105 and extend across said open side. It would be formed preferably of india rubber, though closely woven cloth would serve the purpose. The shield protects the spout from 110 breakage, and the flap or cover preserves its cleanliness.

The side-mouth and spout, though closely connected, are designated separately, because, for some uses, it will be desirable to form the bottle and the spout of different 115 materials, the spout, in that case, to be suitably attached to the container, at the side-mouth.

With all parts so emplaced, in use, a pull at the ring moves the stopper upwardly, 120 such movement being arrested by contact of said margin, or lug, 27, with the spout. The gap or groove in the lower portion of the stopper is now opposite and adjacent to said side-mouth and spout, and only a creeping or tipping of the container is required 125 to pour out the contents, entirely or in part, through the spout, after which, the stopper being pushed back to place, the integral and uncut portion of the stopper descends to the 130

interior space in the neck below the spout and again seals the container. The same acts may be repeated indefinitely.

The mechanism above described could be somewhat simplified; and on the other hand could be of more complicated construction, but the form here described may be adapted to a great variety of uses. For instance, additional to providing the stem with a series of slots and clips of both kinds, either set on the same side or arranged transversely, as previously suggested, an ornamental spool with milled edges may be substituted for the buffer under the stem shoulder. In short, the invention admits of various forms of construction without a departure from its principle.

At 30 is a sieve which may be made of any suitable material and constructed with reference to particular use, and permanently or detachably joined to the stopper within the recess. The sieve may be made with close meshing, and so constituted a strainer for liquids, or with enlarged meshing, when it will serve as a sifter of other substances placed in the bottle. The formation of the recess effects a diminution of the interior end of the stopper, not only making provision for the introduction and attachment of the sieve, but, since the end thus diminished will, when the stopper is elevated in use, rest immediately below and adjacent to the side-mouth, it will break up the mass flowing outwardly and so prevent gurgling in the case of liquids, and clogging in the case of other substances.

The modification, illustrated in Fig. 9 is presented. It involves not the slightest change in the equipment of the stopper if 40 the stopper be shortened and the stem bent and extended over the buffer and above the upper margin of the opening in the cover previously described at right angles and the ring be given the form and function here 45 shown over the spout through the opening 30^a, and used to elevate and lower the closure. In this form of construction a portion of the stem which is thus bent laterally will, of course, have movement, in use, in the slot 50 in the neck of the bottle or container, limited by the range of movement of the cover. A cylinder of wood, fiber or other suitable material might, in that case, be inserted in the space within the bottle neck above the 55 buffer, at 31, or said portion of space might remain vacant.

It is obvious that the cap for the cover now being separated from the stopper will be devoid of the shouldering over the stopper, and will have a flat form as seen at 32. In all other respects, construction and emplacement would be substantially the same in the two embodiments.

I claim:

65. 1. An article as described, comprising a

bottle having a side-mouth in the neck thereof, a stopper carrying a pull member, and a cover for the stopper and neck, said cover being suitably attached to both the bottle on the neck thereof and on the stopper, said stopper and cover being slid able, the stopper within, and the cover on, the neck of the bottle and the stopper having an integral and a diminished end, the integral end adapted, when pressed down full length to seal the bottle below the side-mouth, the diminished end adapted, after elevation of the stopper in the neck preparatory to pouring out the contents of the bottle through the side-mouth to break the continuity of the mass of matter within the bottle and prevent gurgling at the side-mouth when the contents are poured out, if liquid, and clogging, when the contents are other than liquid.

2. In an article as described, the combination with a bottle having a side-mouth in the neck thereof, and a stopper carrying a pull member, of a cover for the stopper and neck, said cover being suitably attached to the bottle on the neck thereof and to the stopper, said stopper and cover being slideable, the stopper within, and the cover on, the neck of the bottle said bottle being slotted between the side-mouth in the neck thereof and the top, said slotted portion being formed to engage the flattened section of the cover, in preventing, in use, rotary movement of the cover and preserving alignment of the recess in the end of the stopper with the side-mouth.

3. An article as described, comprising a bottle, a stopper therefor carrying a pull member, and a cover attached to both, said pull member consisting of a stem having a sharp lower-end point, a ring and shoulder at its upper terminal, and, intermediately, two slots for clips, and carrying winged clips in the slots, one having sharply pointed and sharp edged wings, the other having sharply pointed and blunt edged wings, both clips having narrow necks connecting the wings, having also depending shoulders slotted from the wings, the necks adapted to be fitted into the slots thereby bending the wings upwardly, the sharp winged clip to be placed in the upper and the blunt winged in the lower slot on the stem, and the shoulders adjacently to flattened portions of the stem below the necks, the sharp edged wings adapted to cut into the substance of a stopper with but slight displacement, the blunt edged wings to acutely indent but not to cut the substance, and with perceptible displacement of the substance of the stopper internally, the slots slanted from each side downwardly to a common point, the adjacent upper portions of the stem beveled to allow the wings to recede toward the stem at but a slight variation from the perpendicular in the act of in-

100

introducing the stem and the attached clips to place in a stopper, said clips, in coaction, adapted, upon the application of pull force to the stem, to lift the stopper and cause its upward movement without dismemberment.

- 5 4. The combination with an article as described, comprising a bottle, a stopper, and a cover, of a pull member set in the stopper, said pull member consisting of a stem having a sharp lower-end point, a ring and shoulder at its upper terminal, and, intermediately, two slots for clips, and carrying winged clips in the slots, one having sharply pointed and sharp edged wings, the other 10 having sharply pointed and blunt edged wings, both clips having narrow necks connecting the wings, having also depending shoulders slitted from the wings, the necks adapted to be fitted into the slots thereby 15 bending the wings upwardly, the sharp winged clip to be placed in the upper and the blunt winged in the lower slot on the stem, and the shoulders adjacently to flattened portions of the stem below the necks, 20 25 the sharp edged wings adapted to cut into the substance of a stopper with but slight displacement, the blunt edged wings to acutely indent but not to cut the substance, and with perceptible displacement of the 30 substance of the stopper internally, the slots slanted from each side downwardly to a common point, the adjacent upper portions of the stem beveled to allow the wings to recede toward the stem at but a slight variation from the perpendicular in the act of 35 introducing the stem and the attached clips to place in a stopper, said clips, in coaction, adapted, upon the application of pull force to the stem, to lift the stopper and cause its upward movement without dismemberment.
- 40 5. In an article as described, comprising a bottle, a cover, and stopper, a pull member consisting of a stem having a sharp lower-end point, a ring and shoulder at its upper terminal, and, intermediately, two slots for clips, and carrying winged clips in the slots, one having sharply pointed and sharp edged wings, the other having sharply pointed and blunt edged wings, both clips 45 having narrow necks connecting the wings, having also depending shoulders slitted from the wings, the necks adapted to be fitted into the slots thereby bending the wings upwardly, the sharp winged clip to be placed in the upper and the blunt winged 50 in the lower slot on the stem, and the shoulders adjacently to flattened portions of the stem below the necks, the sharp edged wings adapted to cut into the substance of a stopper 55 with but slight displacement, the blunt edged wings to acutely indent but not to cut the substance, and with perceptible displacement of the substance of the stopper internally, the slots slanted from each side 60 downwardly to a common point, the adj-

cent upper portions of the stem beveled to allow the wings to recede toward the stem at but a slight variation from the perpendicular in the act of introducing the stem and the attached clips to place in a stopper, said 70 clips, in coaction, adapted, upon the application of pull force to the stem, to lift the stopper and cause its upward movement without dismemberment.

6. In an article as described, comprising a bottle, cover and stopper, the stopper carrying a pull member, the combination of a sharp winged and a blunt winged clip, each having engagement in slots formed in the stem of the pull member, and adapted, in 80 combination, and in coaction with each other and the stem, to lift the stopper upwardly in the neck of the bottle, upon application of pull force to the puller.

7. In an article, as described, the combination with a bottle having a single side-mouth, in the neck thereof and a gap in one side of the neck extending from the top down to the side-mouth, the neck being without the usual shoulder, an autonomous cover 90 for a stopper and for the neck, shiftable vertically on the neck within limitations fixed by the cover, the cover adapted to arrest downward movement by means of contact of an interior shoulder in the cap of the cover 95 with the rim of the neck and to arrest upward movement by means of contact of a lug carried on the base of a quadrangular gap in the cover formed to be placed around and about the side-mouth with the underside of 100 the side-mouth, and a stopper, of a pull member carried by the stopper and permanently anchored therein by means of the indenting wings of resilient clips, the clips carried in slots formed in the stem of the pull 105 member.

8. In an article as described, comprising a bottle having a single side-mouth in the neck thereof and a gap in one side of the neck extending from the top down to the side-mouth, the neck being without the usual shoulder, an autonomous cover for a stopper and for the neck shiftable vertically on the neck within limitations fixed by the cover, the cover adapted to arrest downward movement by means of contact of an interior shoulder in the cap of the cover with the rim of the neck and to arrest upward movement by means of contact of a lug carried on the base of a quadrangular gap in the cover 110 formed to be placed around and about the side-mouth with the under side of the side-mouth, and a stopper, a pull member carried by the stopper and permanently anchored therein by means of the indenting wings of 115 resilient clips, the clips carried in slots formed in the stem of the pull member, the pull member adapted by coaction of the stem and clips, upon the application of pull force to the stem, to lift the stopper and 120 125 130

cause its upward movement without dismemberment.

9. An article as described, comprising a bottle, a stopper therefor carrying a pull member and a cover attached to both, said pull member consisting of a stem having a sharp lower-end point, a ring and shoulder at its upper terminal, and, intermediately, slots for clips, and carrying winged clips in the slots the clips having narrow necks connecting the wings, having also depending shoulders slitted from the wings, the necks adapted to be fitted into the slots thereby bending the wings upwardly with the shoulders at rest adjacently to flattened portions of the stem below the necks, the wings adapted to acutely indent with perceptible displacement the substance of the stopper internally, the slots slanted from each side downwardly to a common point, the adjacent upper portions of the stem beveled to allow the wings to approach the stem at but a slight variation from the perpendicular in the act of introducing the stem and the attached clips to place in a stopper, said clips, in coaction, adapted, upon the application of pull force to the stem, to lift the stopper and cause its upward movement without dismemberment.
10. The combination with an article as described, comprising a bottle, a stopper, and a cover, of a pull member carried by and set in the stopper, said pull member consisting of a stem having a sharp lower-end point, a ring and shoulder at its upper terminal, and, intermediately, two slots for clips, and carrying winged clips in the slots the clips having narrow necks connecting the wings, having also depending shoulders slitted from the wings, the necks adapted to be fitted into the slots thereby bending the wings upwardly, the shoulders adjacently to flattened portions of the stem below the necks, the wings adapted to acutely indent with perceptible displacement the substance of the stopper internally, the slots slanted from each side downwardly to a common point, the adjacent upper portions of the stem beveled to allow the wings to approach the stem at but a slight variation from the perpendicular in the act of introducing the stem and the attached clips to place in a stopper, said clips, in coaction, adapted, upon the application of pull force to the stem, to lift the stopper and cause its upward movement without dismemberment.
11. The combination with an article as described, comprising a bottle, a stopper, and a cover, of a pull member carried by and set in the stopper, said pull member consisting of a stem having a sharp lower-end point, a ring and shoulder at its upper terminal, and, intermediately, two slots for clips, and carrying winged clips in the slots, the clips having narrow necks connecting the wings, having also depending shoulders slitted from the wings, the necks adapted to be fitted into the slots thereby bending the wings upwardly, the shoulders adjacently to flattened portions of the stem below the necks, the wings adapted to acutely indent with perceptible displacement the substance of the stopper internally, the slots slanted from each side downwardly to a common point, the adjacent upper portions of the stem beveled to allow the wings to approach the stem at but a slight variation from the perpendicular in the act of introducing the stem and the attached clips to place in a stopper, said clips, in coaction, adapted, upon the application of pull force to the stem, to lift the stopper and cause its upward movement without dismemberment.

of the stopper internally, the slots slanted from each side downwardly to a common point, the adjacent upper portions of the stem beveled to allow the wings to approach the stem at but a slight variation from the perpendicular in the act of introducing the stem and the attached clips to place in a stopper, said clips, in coaction, adapted, upon the application of pull force to the stem, to lift the stopper and cause its upward movement without dismemberment.

12. In an article as described, comprising a bottle, a cover, and stopper, a pull member carried by and set in the stopper consisting of a stem having a sharp lower-end point, a ring and shoulder at its upper terminal, and, intermediately, two slots for clips, and carrying winged clips in the slots, the clips having narrow necks connecting the wings, having also depending shoulders slitted from the wings, the necks adapted to be fitted into the slots thereby bending the wings upwardly, the shoulders adjacently to flattened portions of the stem below the necks, the wings adapted to acutely indent with perceptible displacement the substance of the stopper internally, the slots slanted from each side downwardly to a common point, the adjacent upper portions of the stem beveled to allow the wings to approach the stem at but a slight variation from the perpendicular in the act of introducing the stem and the attached clips to place in a stopper, said clips, in coaction, adapted, upon the application of pull force to the stem, to lift the stopper and cause its upward movement without dismemberment.

Signed at New York, county of New York, and State of New York, this 7th day of December, A. D. 1916.
